CLAIM

The ornamental design for a panel joint, as shown and described.

DESCRIPTION

FIG. 1 is a top, right, front perspective view of a panel joint showing the new design;

FIG. 2 is a front view of the invention illustrated in FIG. 1; FIG. 3 is a right side view of the invention illustrated in FIG. 1;

FIG. 4 is a rear view of the invention illustrated in FIG. 1; FIG. 5 is a left side view of the invention illustrated in FIG. 1;

FIG. 6 is a top view of the invention illustrated in FIG. 1; and,

FIG. 7 is a bottom view of the invention illustrated in FIG. 1.

The broken lines in the drawings depict portions of the panel joint that form no part of the claimed design. The panel joint is shown with symbolic breaks in its height. The appearance of any portion of the article between the break lines forms no part of the claimed design.

1 Claim, 4 Drawing Sheets
